COLLAPSIBLE STEP LADDER
Carlton V. Smith, 11115 SW. 78th, Tigard, Oreg.
Filed May 12, 1961, Ser. No. 109,643
1 Claim. (Cl. 182—156)

This invention relates to a collapsible step ladder, and has as its primary object the provision of a step ladder particularly adapted for exit and entrance to house trailers, pick-up coaches, or the like, provided with foldable steps, and foldable side pieces so that the device can be stored in a relatively compact space.

A further object of the invention is the provision of such a device provided with attaching hooks at the upper end thereof to secure the same to the level of the trailer or the like, the hooks being adjusted longitudinally to accommodate minor variations in height and angularity of the steps of the ladder.

A further object of the invention is the provision of a device of this character wherein the step members are countersunk to the front of the ladder to provide a smooth front.

Still another object of the invention is the provision of an improved foldable step ladder which is sturdy and durable in construction, reliable and efficient in operation, and relatively simple and inexpensive to manufacture and utilize.

Still other objects reside in the combinations of elements, arrangements of parts, and features of construction, all as will be more fully pointed out hereinafter and disclosed in the accompanying drawing wherein:

FIGURE 1 is a perspective view of one form of device embodying this inventive concept shown in operative position.

FIGURE 2 is an enlarged sectional view taken substantially along the line 2—2 of FIG. 1 as viewed in the direction indicated by the arrows.

FIGURE 3 is an enlarged sectional view taken substantially along the line 3—3 of FIG. 2 as viewed in the direction indicated by the arrows.

FIGURE 4 is a fragmentary elevational view of a constructional detail, and

FIGURE 5 is a top plan view of the latter shown in folded or storage position.

Similar reference characters refer to similar parts throughout the several views of the drawing.

Having reference now to the drawings in detail, the ladder of the instant invention is generally indicated at 10 and includes a pair of complementary side rails, each generally indicated at 11. Each side rail is comprised of a front portion 12 and a rear portion 13, which portions are connected along a longitudinal line by hinges 14, so that the portions 13 may fold inwardly relative to the portions 12 as best shown in FIGURE 5. Transversely extending rungs 15 extend between and connect the front portions 12, the rungs being countersunk and beveled as indicated at 16 to impart a smooth front surface. Steps 17 are hinged to each rung 15 as by means of hinges 18, and stop portions 19 and 20 are provided in aligned angular relation on members 12

2

and 13, respectively, to support the steps in the position shown in FIGS. 1 and 2 when the ladder is in operative position.

The arrangement is thus such that with the ladder in the position shown in FIGS. 1 and 2, the steps and the side rails are positioned in operative condition, with the steps in parallel alignment and supported on the supporting blocks 20 to provide an effective and usable ladder. When, however, it is desired to fold the ladder for storage, or when not in use, the steps 17 are swung upwardly to the dotted line position shown in FIG. 2, or the full line position shown in FIG. 3 so that they rest entirely within the confines of the front section 12. The rear sections 13 are then folded inwardly as shown in FIG. 5, thus materially reducing the overall width of the ladder, and allowing it to be stored in a minimum space.

Means are provided for varying the effective length of the ladder, and take the form of slide plates 25, which are provided at their extremities with hook portions 26 which engage over the floor of the trailer or other article to which the device is to be applied. Each plate 25, as best shown in FIG. 4, has a longitudinally extending slot 27 therein through which extends a guide bolt 28, permitting linear movement of the plate 25 to vary the extension of the hooks 26 above the side rails 11. A set screw 30 is provided with a wing nut 31 for clampingly engaging the plates 25 and holding them in a selected position of adjustment.

From the foregoing it will now be seen that there is herein provided an improved foldable step ladder which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

40 I claim:

A collapsible step ladder comprising a first pair of elongated side rails disposed in spaced parallel relation to each other, spaced rungs rigidly connecting said side rails and disposed intermediate the ends thereof, steps hingedly secured to said rungs, stop members secured to each of said side rails adjacent said rungs, a second pair of elongated side rails hingedly secured to said first pair of side rails co-planar therewith, stop members secured to each of said second pair of side rails in alignment with the stop members on said first pair of side rails, said steps supported by said stop members when the ladder is in an erected position, said steps vertically foldable in general alignment with said rungs, said second pair of side rails foldable to overlie said folded steps, and extensible hook members on said second pair of side rails to engage the structure to which the ladder is applied.
